CABINET DOOR HANDLE

Edward H. Roberts, Jeffersontown, and Lawrence R. Collins, Louisville, Ky., assignors to General Electric Company, a corporation of New York

Filed June 14, 1967, Ser. No. 7,478

Term of patent 14 years

(Cl. D67—3)

FIG.1 FIG.2

FIGURE 1 is a side elevational view of the cabinet door handle of the present invention;

FIGURE 2 is a front elevational view of the cabinet door handle of FIGURE 1;

FIGURE 3 is an enlarged sectional view taken along line 3—3 of FIGURE 2;

FIGURE 4 is an enlarged sectional view taken along line 4—4 of FIGURE 2;

FIGURE 5 is an enlarged sectional view taken along line 5—5 of FIGURE 2;

FIGURE 6 is an enlarged sectional view taken along line 6—6 of FIGURE 2; and

FIGURE 7 is an enlarged sectional view taken along line 7—7 of FIGURE 2.

We claim:

The ornamental design for a cabinet door handle, substantially as shown.
